UNITED STATES PATENT OFFICE.

LOUIS H. HONIGBAUM, OF SAN FRANCISCO, CALIFORNIA.

COWL.

SPECIFICATION forming part of Letters Patent No. 617,745, dated January 17, 1899.

Application filed January 19, 1897. Serial No. 619,730. (No model.)

To all whom it may concern:

Be it known that I, LOUIS H. HONIGBAUM, a citizen of the United States, residing at San Francisco, in the county of San Francisco and 5 State of California, have invented certain new and useful Improvements in Ventilators; and I do hereby declare the following to be a full, clear, and exact description of the invention, such as will enable others skilled in 10 the art to which it appertains to make and use the same.

This invention relates to improvements in 15 ventilators, and has more particular relation to ventilators for attachment to the tops of chimneys or ventilating-shafts to prevent the draft from blowing down the shaft or chimney.

The invention consists of certain novel constructions, combinations, and arrangements of parts, all of which will be hereinafter more 20 particularly set forth and claimed.

In the accompanying drawings, forming 25 part of this specification, Figure 1 represents a side elevation of a device embodying my invention. Fig. 2 represents a top plan view 30 of the same. Fig. 3 represents an enlarged detail central vertical section through a portion of the casing containing one of the rubber buffers. Fig. 4 represents a top plan view of one of the apertured lugs for containing the antifriction-balls, and Fig. 5 represents a central vertical section through the same.

A in the drawings represents the attaching- 35 pipe, B the casing surrounding the upper end of the same, and C the protecting hood or guard. The attaching-pipe A may be of any desired construction adapted to be secured to the upper end of a chimney or ventilating-flue. The casing B, which is of 40 greater diameter than the pipe A, is preferably hexagonal in cross-section and is mounted about the upper end of the pipe A by suitable radial arms b, so that there may be a clear draft up about the pipe A between said 45 arms. Said casing B is provided upon each of its sides with a draft-opening b', covered by hinged doors b''. One of these doors is provided with a hinged rod b'', the upper and lower ends of which protrude beyond the upper and lower edges of the door, so that they 50 can be mounted in apertured lugs b⁴ and b⁵, respectively, secured near the upper and

lower edges of the casing. The lug b⁴ comprises an apertured attaching-plate b⁶ and an enlargement b⁷, having a passage b⁸ therethrough. The lug b⁵ comprises an apertured attaching-plate b⁹, having an enlargement b¹⁰, formed with a socket b¹¹, in which is mounted an antifriction-ball b¹², preferably of glass.

It will be observed from the foregoing description that the entire weight of the door falls upon the glass ball b¹², and thus the door may open or close with a minimum amount of friction. Also, the said ball will not cause corrosion in the socket b¹¹, and thus will prevent all noise from the operation of the supporting-rod in said socket. In order to prevent the doors b² slamming shut against the casing B with such force as to cause an abnormal amount of noise, I provide the wall 70 of said casing with a plurality of buffers D. Each of these buffers comprises a headed block of rubber adapted to be slipped through a suitable aperture formed in the casing, so as to protrude in front of said casing and receive the concussion of the door. Each of these blocks is held firmly in position by an attaching-plate d, that is passed about the rear head of said block and secured to the casing by suitable screws or rivets d'. The doors b² upon diametrically opposite sides of the casing B are connected by pivoted rods b¹³, so that as the door upon one side is blown closed the companion door upon the opposite side is opened. This peculiar construction 85 is to prevent the wind blowing the smoke and other products of combustion down the chimney, as only the doors away from the wind are open, and thus a complete suction at the top of the chimney is established.

The guard C has an upper and lower conical surface and is of slightly-greater diameter than the pipe A, and is mounted in the upper end of the casing B by suitable radial arms c. The office of the upper conical portion of the said guard is to provide a perfect water and snow shed, while the under conical portion is intended to divert the smoke and other products of combustion from the center of the shed toward the periphery, so that they may readily discharge out of the top of the casing B.

It will also be observed that this ventilator will be automatically operated by the direc-

tion of the wind and only the doors or shutters upon the lee side of the casing B opened. At the same time this operation of said doors will be accomplished without any noise or 5 concussion because of the antifriction-bearings and the rubber buffers.

A material advantage results from making the casing hexagonal in cross-section for the reason that the wind can act upon only three 10 sides thereof and the other three sides will be protected, so that the doors which cover the openings in the lee sides may remain open and not be affected by the wind, which would cause the doors to continually blow to. 15 In devices of a similar nature heretofore employed in which the casings are square the wind can obtain access to as many as three of the doors at one time, and as a result at least two of the doors will be alternately 20 opened and closed continuously by the action of the wind, thus making a disagreeable slamming noise and causing unnecessary wear on the parts.

Having thus described my invention, what I claim as new, and desire to secure by Letters 25 Patent, is—

In a ventilator, a casing hexagonal in cross-section and provided in each side with a draft-opening, in combination with a corresponding series of doors hinged on vertical axes at 30 the sides of said openings and designed to close the same, a series of rods connecting the doors in opposite pairs, and a protecting-cone arranged at the upper end of the casing, said cone being of less diameter than the casing 35 so as to leave a surrounding space and being of greater diameter than the flue-pipe, substantially as and for the purpose described.

In testimony whereof I have signed this specification in the presence of two subscribing 40 witnesses.

LOUIS H. HONIGBAUM.
